UNITED STATES PATENT OFFICE

2,459,015

AUTOMATIC SWITCH

Clyde H. Clement, Phoenix, Ariz., assignor of
one-half to Cleo R. Cox, Phoenix, Ariz.

Application August 14, 1945, Serial No. 610,771

1 Claim. (Cl. 200—142)

1

This invention relates to a safety switch and circuit construction for motion picture houses.

An object of this invention is to provide an improved switch construction which is connected to the electric circuits of projection machines, the fire alarm system and other electric circuits so that in the event of fire the fire alarm, which may be remote from the projection room, will be energized and the main house lights, which are normally cut off during the showing of a picture, will be turned on in order that people in the theater will be able to leave the theater more rapidly than is the case where they leave the theater with the lights off.

A further object of this invention is to provide an improved switch structure of this kind which is simple in construction, and automatically moves from a normal position closing the electric circuits to the projection apparatus to a disengaging position cutting off the projection apparatus and closing the fire alarm circuit and other circuits associated therewith which are normally off during the operation of the projection apparatus.

A further object of this invention is to provide a switch of this kind which is normally held in uppermost position closing the normal circuits by a frangible connection which is connected to the shutter bar which automatically closes the shutter in the forward wall of the projection booth.

With the foregoing objects in view, and others which may hereinafter more fully appear the invention consists of the novel construction, combination and arrangement of parts as will be more specifically described, and illustrated in the accompanying drawings wherein are shown embodiments of the invention, but it is to be understood that changes, variations and modifications may be resorted to which fall within the scope of the invention, as claimed.

In the drawings:

Figure 1 is a detail front elevation of a switch constructed according to an embodiment of this invention.

Figure 2 is a detail side elevation, partly broken away and in section, of the switch.

Figure 3 is a sectional view taken on the line 3—3 of Figure 2.

Figure 4 is a sectional view taken on the line 4—4 of Figure 2.

Figure 5 is a sectional view taken on the line 5—5 of Figure 1.

A switch assembly, generally designated as 25, is interposed in the circuits of the motors, lamps

2

and switch for the fire extinguisher in a projection room, and includes an upper stationary insulated body 26 which is adapted to be secured by fastening members 27 to a panel 28.

A lower stationary body 29, of insulated construction, is also secured to the panel 28 by fastening members 30 in a position spaced downwardly from the upper body 26. The upper body 26 has secured thereto pairs of contact members 31, 32, 33 and 34. The contact members 31 to 34 are secured to bolts or terminals 35, 36, 37 and 38 which are positioned above the body 25. The lower stationary body 29 has mounted on the upper side thereof spaced pairs of contact members 39, 40, 41 and 42, which are carried by terminal members 43, 44, 45 and 46 respectively.

An intermediate movable insulated body 47 is disposed between the two bodies 25 and 29 and has secured to the upper side thereof a plurality of contact bridging members of substantially U-shape and designated by the numerals 48, 49, 50 and 51.

The several bridging members 48 to 51 are secured in recesses 52 which are formed in the body 47 being secured in the recesses 52 by screws 53 which are threaded into embedded nuts 54 carried by the body 47. The bridging member 48 is adapted to bridge the pairs of contacts 31 and the bridging member 49 bridges contacts 32. The bridging member 50 bridges contacts 53, and the bridging member 51 bridges contacts 54.

A plurality of inverted U-shaped bridging members 55, 56, 57 and 58, which are similar in construction to the bridging members 48 to 51, are disposed in a recess 59 formed in the lower side of the body 47, and secured therein by fastening screws 60 which are threaded into embedded nuts 61.

Bridging member 55 bridges the two contacts 39; bridging member 56 bridges the two contacts 40; bridging member 57 bridges the two contacts 41; and bridging member 58 bridges the two contacts 42.

The movable contact carrier 47 is fixedly secured to a pair of vertically disposed bars 62 and 63 which are slidable through openings in the stationary bodies 25 and 29, and are fixed to the contact carrier 47 by set screws 64 and 65 respectively.

The carrier 47 is constantly urged downwardly to a position where the bridging members 55 to 58 will bridge the contacts 39 to 42 by means of springs 66 and 67 which, at their upper ends, bear against the lower side of the lower body 29, and at the lower ends bear against tensioning

nuts 68 and 69 threaded on the lower ends of the slide bars 62 and 63 respectively.

A connecting bar 70 connects the upper ends of the slide bars 62 and 63 together being secured on the ends of these bars by nuts 71 and 72. The center of the bar 70 has an eye 73 secured thereto and one end of a spring 74 is engaged with the eye 73. A link 75 is connected at its upper end to a lever arm 76 carried by the shutter operating bar 24 and a fusible member 77 is connected between the spring 74 and the lower end of the link 75.

The spring 74, with the linkage connecting this spring with the lever arm 76, are adapted to maintain the movable circuit-breaking and closing carrier 47 in its uppermost and normal operating position.

The upper terminals 35 to 38, which are in pairs, have one member of each pair connected to a common supply wire 78 by means of wires 79, 80, 81 and 82. The other member of pair 35 is connected by means of a wire 83 to one side of the motor 10, and the other member of pair 36 is connected by a wire 84 to one side of the lamp 12. The other sides of the motor and lamp are connected to the ground through a common ground wire 85. The other member of pair 37 of terminals is connected by means of a wire 86 to one side of the lamp 13, and the other member of the pair 38 is connected by means of a wire 87 to one side of the motor 11. The other sides of the motor 11 and the lamp 13 are connected to a return or ground by a common conductor 88.

One member of each of the lower pairs of contacts 39 to 42 are connected to the positive side of the supply source by means of conductors 89, 90, 91 and 92. The wires 89 to 92 are connected through a common wire 93 to the supply wire 78. A wire 94 connects the other member of the pair of contacts 39 to the main houselight circuit, being adapted to form a shunt in this circuit for closing the circuit irrespective of the position of the main house switch.

The other member of the pair of contacts 40 is connected by means of a conductor 95 to one side of the solenoid or electric operator 96 for the valve 23. The opposite side of the operator 96 is connected to the return line by a ground 97. The other member of the pair of contacts 41 is connected to a slide lamp by means of a conductor 98. The slide lamp may be a projection apparatus for projecting still pictures on the screen, or for projecting instructions or other material onto the screen during an emergency, such as a fire, or the like.

The other member of the pair of contacts 42 is connected to a fire alarm system by means of a wire 99 so as to close the circuit to the fire alarm when the carrier 47 is lowered to its lowermost emergency position.

In the use and operation of this switch structure the several terminals are connected to the circuits, as hereinbefore described, and in the normal operating position the carrier 47 is in its uppermost position whereby the projection ap-

paratus may be operated in the normal manner and the projection apparatus may be disengaged from the supply source by means of a main switch 100 which is interposed in the positive wire 78.

In the event a fire should occur in the projection room so as to either cause the shutter bar 24 to rotate in a clockwise direction, as viewed in Figure 2, or the heat in the projection room should cause fuse 77 to melt, spring 66 and 67 will move carrier 47 downwardly so as to cut off the electric circuits to the projection motors and the lamps and at the same time to close the circuits to the valve operator connected with the carbon dioxide tank and to the fire alarm, the main houselight circuit and the slide lamp circuit.

It will be understood that additional circuits may be closed or broken, as may be desired, it only being necessary to add additional pairs of contacts with bridging members to the carrier 47 and the stationary bodies 25 and 29.

I claim:

An automatic switch for use in connection with the shutter holding rod of a motion picture projection room comprising a pair of fixed insulated stationary bodies disposed in spaced relation one to the other, pairs of contacts carried by the confronting sides of said bodies, a movable circuit closing member disposed between said bodies, bridging contacts carried by one side of said member for engagement with the contacts of one of said bodies, oppositely disposed bridging contacts carried by the opposite side of said member for engagement with the contacts of said other body, a pair of slide bars fixed to said member and loosely engaging through said bodies, a connecting bar connecting the end of one bar to the other bar, springs about said pair of bars outwardly of one of said bodies for constantly urging said member to move in the direction of the other of said bodies, elongated yieldable means connected between said connecting bar and said shutter holding rod for normally maintaining said member in a position with the bridging contacts on the first-named side thereof in engagement with the pairs of contacts of said other body and a fusible element interposed in said latter named means.

CLYDE H. CLEMENT.
